UNITED STATES PATENT OFFICE.

CHARLES BIRTH, OF KINGSTON, PENNSYLVANIA, ASSIGNOR TO WALES ADDING MACHINE COMPANY, OF WILKES-BARRE, PENNSYLVANIA, A CORPORATION OF PENNSYLVANIA

CALCULATING MACHINE.

1,386,758.

Specification of Letters Patent. Patented Aug. 9, 1921.

Application filed October 13, 1919. Serial No. 330,371.

To all whom it may concern:

Be it known that I, CHARLES BIRTH, a citizen of the United States, residing in the borough of Kingston, Luzerne county, Pennsylvania, have invented new and useful Improvements in Calculating-Machines, of which the following is a specification.

The invention is especially directed to accumulating mechanisms for calculating machines, and while designed as an improvement upon the mechanism disclosed in the U. S. application of Pentecost and Fisher filed July 17, 1918, Serial No. 245,273, is not restricted in its use to that machine.

15 In general, the main object of the invention is to render the calculating machine more accurate and efficient, as well as to enable it to perform its functions more rapidly and positively.

20 These advantages my invention attains by affording the trip members which control the carrying or transferring action, a better hold or grip against the carrying member detents, whereby to reduce to a minimum, the possibility of overcarrying, and to eliminate the necessity of taking an extra or idle stroke intermediate an adding operation and a totaling or clearing operation.

By avoiding the requirement for taking 30 this extra stroke, time is saved in the operation of the machine, and an economy in paper is effected.

By affording a better contact between the trip members and the carrying member 35 detents, close points are avoided and the machine can be timed to operate at higher speeds, owing to the reduced liability of the accidental escape of the trip members past their detents.

40 My invention affords a firm contact between the trip members and the carrying detents, in totaling and clearing operations, whereby to arrest the counters in their zero positions, irrespective of the position of the carrying member detents.

The invention further includes certain other novel features and combinations of parts, all of which will be more fully disclosed hereinafter and particularly pointed 50 out in the claims.

In the accompanying drawings, Figure 1 is a longitudinal sectional view through a part of a calculating machine, showing the

keyboard or indexing mechanism and the accumulating mechanism, of which latter 55 my invention forms a part;

Fig. 2 is an enlarged detail side view of the accumulating mechanism, in its normal position of rest;

Fig. 3 is a detail perspective view of one 60 form of my carrying and total alinement detent, disassembled;

Fig. 4 is an enlarged detail side view, similar to Fig. 2, showing the positions of the parts at the end of the forward stroke 65 of the machine, in an adding operation; and

Fig. 5 is a detail side view of the carrying mechanism alone, showing the positions of the parts at the end of a carrying operation.

Calculating machines of the Wales type, 70 as illustrated in the application of Pentecost and Fisher, filed July 17, 1918, Serial No. 245,273, include a keyboard or selective mechanism and an accumulating mechanism.

The keyboard comprises a series of depressible numeral keys 117 (Fig. 1) arranged in denominational rows. Individual levers 116 connect the respective keys in each row with the corresponding stops 115 in the respective denominational rows or files of 80 stops, the upper ends of which extend through the cross plate of a housing 113 located at the rear of the keyboard.

Depressing the numeral keys 117 in accordance with the amount to be registered 85 in the accumulating mechanism, rocks the levers 116 to project the corresponding stops 115 in the respective denominations, farther above the housing 113 and into the paths of rack-positioning bars 310, to variously determine the advance of the latter.

Denominational rack-arresting detents 221 journaled on a cross shaft 202, overlie each denominational file of stops 115, and are displaceable by the stops. The rack-arresting detents normally oppose their respective positioning bars 310 to arrest the latter when no keys have been depressed in any of the several denominational rows.

The denominational positioning bars 310 100 are each pivotally supported at points 351 and 350 in a substantially horizontal plane, by front arms 312 and rear arms 311 individual to the several positioning bars. The front arms 312 are journaled for independent rocking, on a cross shaft 300, and

the rear arms 311 are similarly journaled on a cross rod 301 parallel with the cross shaft 300.

The stocks 410^m of denominational adding racks or drive members 410 are individually journaled on a cross rod 401 located intermediately of, and in substantially the same horizontal plane with, the cross shaft 300 and cross rod 301. The drive racks 410 lie alongside their respective positioning bars 310, to which they may be conveniently secured by means of a slot and pin connection 450.

Restoring links 312^a depend from extensions 312^m of the respective front supporting arms 312, the links being forked at their lower ends to embrace a restraining and restoring bar 294 carried by the forward ends of a pair of levers 220 journaled on a cross rod 508^a. A slotted anchor plate 220^b secured to the restraining and restoring bar 294 and common to the series of restoring links 312^a, affords a spacing guide for the several links 312^a. Springs 383 flexibly connect the links and the anchor plate, and tend to rock the arms 312 forwardly to thereby advance the positioning bars 310 and the driving members 410 connected thereto.

Radius bars 323 journaled on the cross shaft 300, carry rolls or travelers 340^a entered in cam slots 220^m formed in the levers 220. A trip rod 303 extends between the radius bars, and links 214 connect the rod 303 with cranks 212 on the main drive shaft 200. A main restoring spring 285 connected to the main drive shaft 200, tends to maintain the shaft in its home position, and the main drive shaft, in turn, through cranks 212 and links 214, normally retains the swinging radius bars 323 at their rearward limit of travel. The travelers 340^a of the radius bars 323 are thus held near the rear ends of the cam slots 220^m in the levers 220, to maintain the levers 220 and the restraining and restoring bar 294 carried thereby, in their elevated positions. The restraining and restoring bar contacts the forked restoring links 312^a, to retain the latter in raised position against the tensions of the positioning bar drive springs 383 and through such links, and the supporting arms 312, the positioning bars 310 and drive members 410 are held retracted.

Turning the main drive shaft 200 forwardly against the tension of the main drive spring 285, draws the links 214 and radius bars 323 forwardly to cause the rolls 340^a to traverse the cam slots 220^m and rock the levers 220 and the restraining and restoring bar 294 downwardly. The anchor plate 220^b, moving downwardly with the restraining and restoring bar 294, further tensions the drive springs 383 to draw the links 312^a downwardly and swing the arms 312, 311 forwardly, thereby effecting the advance of

the positioning bars 310 and drive members 410, until the positioning bars and drive members are arrested by the contact of the forward ends of the bars with the stops 115 projected into their paths by the depression of the keys 117, or with the rack-arresting detents 221 in those denominations wherein no keys have been depressed. The arrest of any of the positioning bars 310 with their connected parts, including the links 312^a, merely results in further tensioning the corresponding drive springs 383, as the restraining and restoring bar 294 moves relatively to the arrested links 312^a in completing its stroke.

At the end of the forward stroke, the main drive shaft 200 is released to the action of the restoring spring 285, which reverses the direction of rotation of the shaft and its cranks 212, to return the positioning bars 310 and drive members 410 to their home positions. The cranks 212 press the links 214 backwardly to swing the radius bars 323 rearwardly. The travelers 340^a retrace their paths in the cam slots 220^m to raise the levers 220, together with the restraining and restoring bar 294. The latter presses against the lower ends of the links 312^a to force the latter upwardly and retire the positioning bars 310 and drive racks 410 to their normal positions of rest.

The particular machine herein selected to illustrate my invention, includes a plurality of sets of counters which coact with the drive members 410 to accumulate separate lists of amounts, for instance, but I wish to specifically state that the invention is as readily applied to machines having a single set of counters, and shall limit the following description as far as practicable, to a machine having a single set of counters.

Front and rear series of denominational counters 490, 490^x are individually journaled for independent rotation on their respective axles 409, which are mounted in the free ends of the respective opposed sets of arms 414 journaled on the respective cross rods 404. The several series of counters 490 and 490^x are arranged adjacent their corresponding drive members 410, and pinions 435, associated to turn with each counter, and arranged above and in the same vertical planes with their corresponding drive members 410. They are adapted to engage with and disengage from their denominational drive members.

Normally, the counters 490, 490^x are held in their elevated positions with their pinions 435 out of mesh with or disengaged from the drive members 410, as shown in Fig. 2.

In an adding operation, the counters 490^x, for example, remain in elevated position, disconnected from their drive members during the advance of the positioning bars 310 and drive members 410, but at the end of such forward stroke, and after the position-

ing bars have completed their advance, the counters 490* drop to mesh their pinions 435 with the drive members 410.

The positioning bars 310 and drive members 410, during their retirement to their home position, on the return stroke of the main drive shaft, turn the pinion 435 and counters 490* through angles of rotation corresponding to the distances through which 10 the drive members have previously advanced on the forward stroke, to register on the counters, the amount set up on the keyboard. Near the end of the return stroke of the main drive shaft 200, and after the complete 15 retirement of the drive members 410, the counters 490* and their pinion 435 disengage from the drive members preparatory to the next operation.

The mechanism whereby the counters 490, 20 490* and their pinions 435 are supported in idle position above the drive members 410, the means for effecting the engagement and disengagement of the pinions and drive members, and the means for selecting which 25 set of counters, if any, shall become operative, form no part of the present invention, and are not shown. For a complete description of convenient means to accomplish these ends, attention is directed to the application 30 of Pentecost and Fisher, Serial No. 245,273, filed July 17, 1918.

To prevent accidental rotation of the counters 490* when the latter are disconnected from their drive members 410, and 35 also to effect the transfer of excess "ones" from the counters of lower denominations to the counters of next higher denominations, in the usual process of carrying, it is customary to provide a combined counter- 40 detaining and carrying member for each counter. One form of such combined counter-detaining and carrying member is illustrated in my U. S. Patent No. 1,318,641, dated October 14, 1919. In the present in- 45 stance, each carrying member for the respective counters 490, 490* comprises a bar 610 or 610* (Figs. 2, 4 and 5) extending longitudinally of the machine and over its respective counter pinion 435, the opposite 50 ends of the bars 610, 610* being slotted to accommodate and slide transversely of the parallel cross rods 600, the bars being provided with teeth 610* at that portion of their lower edges which are directly above their 55 respective pinions 435. The pinions, as they disengage from their drive members 410, engage with the teeth 610* of their carrying and detaining members 610, 610*, and are thereby locked against accidental rotation. 60 Springs 680 connected to the forward ends of the several carrying bars 610, 610* and to a stationary anchor plate 693, tend to draw the carrying and detaining members 610, 610* forwardly, to turn their respective 65 counters 490, 490* one step to add "one"

thereon, whenever the amount added to the counter of next lower denomination in the same set of counters, exceeds the capacity of such counter.

This type of transfer mechanism requires 70 the provision of means to releasably lock the carrying members 610, 610* in set or cocked position against the tensions of the drive springs 680, which means is also utilized to arrest the counters in their zero positions, 75 in clearing, totaling and sub-totaling operations, and my invention relates particularly to the improvement of such means.

Pursuant thereto, and referring to the single set of counters 490*, instead of employing the former rigid carrying-bar detent, I provide a flexible detent mechanism, 80 whereby I attain the various advantages set forth.

In my invention, the carrying detents each 85 include a detaining element 612^g pivotally mounted at one end on the cross rod 600, or on a hub projecting from one side of a spacing collar 632 (Fig. 3) journaled on the cross rod. The detaining element extends alongside its associated carrying member 610^a and is provided near its free end with a lateral latching lug 612^m adapted to overlie the upper edge of the carrying member 610^a in front of a shoulder 610^p formed 90 on the upper edge thereof. A spring 681^b connected to the detaining element and to its carrying member 610^a, holds the latching lug 612^m yieldingly in place. 95

Adjacent the detaining element 612^g and 100 parallel therewith is a trigger 612^e likewise journaled on the cross rod 600 or on a hub projecting from the opposite face of the collar 632. A pin 651^b carried by the detaining element 612^g projects through an 105 enlarged opening 612^r formed in the trigger 612^e, and a spring 681 holds the trigger in depressed position with the upper end of the opening in contact with the pin 651^b. The free end of the trigger 612^e carries a combined release lug and abutment 612^s offset 110 therefrom and lying at an angle to the latching lug 612^m, and in the path of a tripping cam or member 411 associated with the counter 490* of next lower denomination, it 115 being understood that each counter 490* is provided with a tripping and arresting cam 411 which turns and shifts with the counter.

It has been pointed out that the series of 120 counters 490* are bodily shiftable between the carrying members 610^a and the drive members 410. In order to reduce to a minimum the distance through which the counters travel in disengaging from the carrying members 610^a and engaging the drive 125 members 410, and vice versa, and thereby reduce the time during which the counters are uncontrolled and may therefore accidentally turn, the application of Pentecost and Fisher, hereinbefore referred to, shows an 130

arrangement whereby the bodily travel of the counters is shortened to a movement substantially equal in length to the height of a tooth of the pinion 435 plus sufficient clearance to prevent contact of the drive member 410 with the teeth of the pinion when the drive member advances in adding operations, and to prevent contact of the teeth of the pinion with the carrying bar 610^a, when the pinion is in mesh with and rotated by its drive member. As the depth of tooth of the pinion is much greater than the clearance above mentioned, it is obvious that the lower teeth of the pinion, when the latter disengages from the carrying member 610^a and engages the drive member 410, will enter between the teeth of the drive member prior to the complete disengagement of the upper teeth of the pinion from the carrying member, and vice versa.

Obviously, the trip cams 411, being connected to turn with their respective counters 490^x, are subject to this bodily movement of the counters away from and toward the carrying members 610^a, the latter being supported by the cross rods 600 against movement toward and from the drive members 410.

And hence the trip cams 411, in dropping with their counters 490^x and pinions 435 when the pinions mesh with the drive members 410, shift relatively to the carrying bar detents 612^c which normally restrain the carrying members 610^a in cocked or set position.

All carrying operations must be initiated while the counters 490^x are engaged with their drive members 410, at which time they are disengaged from their carrying members 610^a, but the carrying operations are not completed, until the counters are engaged with their carrying members, at which time they are disengaged from their drive members.

A carrying operation once started, may, and often does continue across one or more successively higher denominations of counters, depending upon the amount already registered and the amount added thereto by the last operation.

Assuming the rotation of a counter 490^x of lower denomination from its "9" to its "0" position, during an adding operation, and hence while engaged with its drive member 410, the trip cam or member 411, turning with the counter 490^x, wipes against the release lug 612^a of the overhanging trigger 612^c and forces the latter upwardly, at first, against the tension of its spring 681 only, but later, when the lower edge of the enlarged opening 612^r strikes the pin 651^b connecting the trigger 612^c with its associated detaining or latching member 612^g, the cam 411, in addition, lifts the latching member 651^b against the tension of its spring 681^b and

the resistance caused by the frictional engagement of its latching lug 612^m and the spring-pressed shoulder 610^p of the carrying member 610^a, to disengage the latching lug from the shoulder and free the carrying member associated with the counter of next higher denomination, to the action of its drive spring 680.

The trip member 411 lifts the flexible carrying detent until the point of the trip member finally escapes past the release lug 612^a during the continuation of the curvilinear travel of the trip member from its "9" to its "0" position, whereupon the spring 681^b restores the latching element 612^c until the latching lug 612^m strikes the upper edge of the shouldered portion of the carrying member 610^a, on which it rides during the advance of the carrying member when adding "1" to the counter of next higher denomination, and during the restoration of the carrying member. Furthermore, it is to be particularly noted, that the spring 681 depresses the trigger 612^c with its combined release lug and abutment 612^a immediately upon the escape of the trip cam 411, until the trigger is arrested by the contact of the upper edge of the enlarged opening 612^r with the pin 651^b.

To permit the carrying member 610^a to completely advance under the influence of its drive spring 680, at this time, would be of no avail, since the counters 490^x are as yet out of engagement with the carrying members 610^a and in engagement with their drive members 410, and the carry would be lost.

It is necessary, however, to permit the carrying members 610^a a slight advance when their latching lugs 612^m are released, to prevent the restoration of the latching lugs to effective position in front of the shoulders 610^p, upon the escape of the trip cam 411 past the release lugs 612^a.

Consequently, a combined carry-resetting and delaying mechanism is provided, suitably operated in relation to the times of engagement and disengagement of the counters 490^x with their drive members 410 and their carrying members 610^a.

Such carry-resetting and delaying mechanism, as shown more clearly in the above-mentioned application of Pentecost and Fisher, may conveniently include a bar 613 mounted on a carrier 690 extending across the machine in front of the forwardly-projecting ends of the carrying members 610^a, and supported at its opposite ends by inclined arms 611^a journaled on the intermediate shaft 401.

The depending arms of actuating bell crank levers 611^b, pivoted on suitably supported studs 652, carry laterally-extending thrust ears 652^a overhung by the inclined supporting arms 611^a which rest against

the thrust ears. These ears limit the throw of the supporting arms 611^a and carry-resetting bar 613 in one direction. Operating links 611^b, pivotally connected at their upper ends to the remaining arms of the bell cranks 611^c, are provided with closed slots 611^m at their lower ends to embrace studs 250 mounted in the cam-slotted levers 220. Springs 685^a connected to the carry-resetting bar 613 and to the anchor plate 693, tend to withdraw the resetting bar to that limit of its throw farthest from the projecting ends of the carrying bars 610^a, and operate to retain the resetting bar in such idle or retracted position while the levers 220 remain in their normal elevated positions, as shown in full lines in Fig. 2, at which time, the studs 250 in the levers 220 lie near the upper ends of the slots 611^m in the operating links 611^b, and the counters 490^a are in mesh with their carrying members 610^a.

During the forward stroke of the main drive shaft 200, the counters 490^a being engaged with their carrying members 610^a, to permit carrying operations, the levers 220 swing downwardly, and the studs 250 idly descend in the slots 611^m until near the end of the forward stroke and subsequently to the disengagement of the pinions 435 and their counters 490^a from the carrying members 610^a, and their engagement with the drive members 410, the studs 250 contact the lower ends of the slots 611^m to draw the operating links 611^b downwardly and rock the bell cranks 611^c to swing the supporting arms 611^a and the carry-resetting bar 613 rearwardly to the opposite end of its travel. The carry-resetting bar contacts the forward ends of the carrying members 610^a to restore to set position all those which have been discharged during the preceding operation, whereupon the latching lugs 612^m of the corresponding detents 612^a, which have been riding on the shoulders 610^a of their discharged carrying members, drop in front of the shoulders under the influence of their springs 681^a and 681 to lock the carrying members in cocked position.

If the carry-resetting and delaying member 613 remained at the limit of its resetting travel, it would retain the tripped carrying members 610^a in cocked position, and the carrying member detents 612^a displaced by the trip members 411 on the counters 490^a, during the retirement of the drive members 410 while the counters are engaged therewith, would return to effective latching position after the trip members 411 escaped past the release lugs 612^a.

Therefore, the main drive shaft 200, at the beginning of its return stroke, and prior to the rotation of the counters, starts the levers 220 upwardly, thereby raising the studs 250 and permitting the bar-resetting spring 685^a to commence the withdrawal of the resetting

bar 613 from contact with the front ends of the cocked carrying members 610^a. Such withdrawal, however, is arrested after the carry-resetting bar has backed away but a short distance, by the engagement of spring-pressed arresting bars 611^e with lugs 611^v on the operating links 611^b, the forward ends of the arresting bars being provided with graduated shoulders 611^s, 611^t, the lower shoulders 611^u lying over the lugs 611^v to prevent further withdrawal of the resetting bar 613 at this time.

The arresting bars 611^e retain the carry-resetting bar 613 in such intermediate position, as the levers 220 continue to rise under the influence of the radius arms 323, the studs 250 in the levers 220 idly traversing the slots 611^m in the operating links 611^b until, near the end of the return stroke of the main drive shaft, and after the disengagement of the pinions 435 and counters 490^a from their drive members 410, and their engagement with their carrying members 610^a, the trip rod 303 contacts lips 611^p on the spring-pressed arresting bars 611^e to retract the arresting bars and free the operating links 611^b and carry-resetting bar 613 to the action of the restoring spring 685^a, which immediately snaps the bar 613 to its idle position.

The arrest of the carry-resetting bar 613 in its intermediate position during the return stroke of the main drive shaft and the coincident retirement of the drive members 410 and rotation of the counters 490^a, permits the slight advance of any of the carrying bars 610^a which may have been released by the action of the trip cams 411 during the rotation of the counters from "9" to "0" position, and holds such tripped carrying members against completing their advance, until the counters 490^a and pinions 435 have again engaged their carrying members.

Such slight advance of the tripped carrying members 610^a also enables them to interpose their shoulders 610^a beneath the latching lugs 612^m of the tripped detents 612^a to prevent the immediate restoration of the detents to effective position when the trip members 411 escape past the release lugs 612^a.

After the engagement of the counters and carrying members, the complete withdrawal of the resetting bar 613 frees the tripped carrying members 610^a to advance a sufficient distance to add "1" to their corresponding counters.

The carry-resetting bar remains in such withdrawn or idle position until near the end of the next forward stroke of the main drive shaft, as heretofore explained.

If the counter 490^a whose associated carrying member 610^a is tripped, registered "9" before the operation of its carrying member, the carrying member will turn its counter from its "9" to "0" position while the counter is in en-

gagement therewith and disengaged from its drive member, and the tripping member 411 of such actuated counter will, in turn, displace the detent 612^g appropriated to the 5 carrying member correlated with the counter of next higher denomination, to release its carrying member 610^a to the action of its drive spring 680. There being no occasion for delaying the transfer onto such counter 10 of higher denomination, since the counters are engaged with their carrying members, the last-named carrying member is free to advance its full travel to add "1" to its counter.

15 It will be noted that whereas the first or initial carry was initiated while the counters were engaged with their drive members and disengaged from their carrying members, the second carry is wholly effected while the 20 counters are engaged with their carrying members and disengaged from their drive members.

In direct carrying operations wherein the detents are tripped while the counters are 25 engaged with their drive members, the power which actuates the counters and their trip members to displace the spring-pressed detents, is derived from the main restoring spring 285 and is quite sufficient to overcome 30 the resistance of the detent springs 681, 681^b plus the friction caused by the pressure of the shoulders 610^p of the spring-driven carrying members 610^a against the latching lugs 612^m of the detents.

35 In cross-carrying, however, which occurs only when the counters 490^x are engaged with their carrying members 610^a, the drive spring 680 of the carrying member 610^a of lower order must overcome the tension of 40 the detent springs 681, 681^b pertaining to the carrying member 610^a of next higher order, plus the friction between the detent and its carrying member, and the friction between the abrupt cam edge of the trip member 411 on the counter of lower order 45 as it wipes against the releasing lug 612^s of the detent of next higher order, it being obvious that the tension of the drive spring 680 for the carrying member of lower order 50 is progressively decreasing as it drives its carrying member 610^a forwardly to turn its associated counter from "9" to "0".

In the Pentecost and Fisher application above referred to, this condition is remedied 55 by arranging the carrying member springs 680 so as to progressively increase the tension thereof from the highest to the lowest order.

Obviously, the releasing lugs 612^s of the 60 carrying member detents 612^g lie farther within the paths of the trip members 411 when the counters 490^x are engaged with their carrying members 610^a than when disengaged therefrom, and the trip members 65 411 must be of sufficient length to displace

their detents 612^g when the trip members are in their remote positions (engaged with the drive members) as well as when in positions adjacent to the detents, (when engaged with their carrying members).

In both cases, the beveled edges of the trip members 411 wipe along the releasing lugs 612^s of the triggers 612^e to raise the latter and the latching members 612^s to which they are flexibly connected, a distance equal to the 75 height of the shoulders 610^p on the carrying members 610^a, plus an added distance forming a safety clearance to avoid close points. The extent of such safety clearance depends upon whether the counters 490^x are engaged 80 with their carrying members 610^a (at which time the clearance is greatest) or with their drive members 410.

In totaling and clearing operations, the counters 490^x are engaged with their drive members 410 at the beginning of the forward stroke of the main drive shaft and prior to the advance of the drive members, instead of at the end of the forward stroke. The drive members, on their advance, reverse the 90 direction of rotation of the counters, until the rear edges of the trip members 411 of the counters contact the front faces of the releasing lugs 612^s, to arrest the counters 490^x in zero position.

At the end of the forward stroke of the main drive shaft, the actuating springs 383 of the drive members press the rear edges of the trip members 411 firmly against the front faces of the releasing lugs 612^s on the respective carrying member detent triggers 612^e. The counters 490^x are disengaged from their drive members 410 and reengaged with their carrying members 610^a at the beginning of the return stroke of the main drive shaft, the rear edges of the trip members sliding transversely along the front faces of the release lugs 612^s, at which time the tension of the drive member springs 383 is but slightly relaxed. Consequently, the tendency of the drive members 410 on the forward stroke, is to turn the counters 490^x past their zero positions and the trip members 411 must have a firm contact with the releasing lugs 110 612^s on the detent triggers 612^e to prevent 115 such action.

In rapid totaling and clearing operations of the machine, under former constructions, the trip members 411 forcibly contact their 120 detents and there is the possibility that one or more will either displace their detents entirely, thereby effecting overcarries, or will partly displace their detents sufficiently to permit the trip members to escape past 125 the releasing and arresting lugs, in either of which events the counters will not be cleared.

Heretofore, I have considered merely the 130 action of the trip members 411 against the

releasing lugs 612^s of the carrying member 610^a when the counters and their trip members are either adjacent to or remote from their detents, it being assumed that the detents are in their effective locking positions, but the situation is further complicated by the fact that the detents themselves assume either of two positions, relatively to the trip members, that is, the detents may be in their effective positions, wherein the latching lugs 612^m lie in front of the shoulders 610^p of the carrying members 610, or in their ineffective positions, to which they have been shifted, so that their latching lugs 612^m rest idly upon the shoulders 610^p of the carrying member, and thereby hold the releasing lugs 612^s farther away from the axis of the trip members 411. Thus, after the trip member 411 displaces the detent, the carrying member 610^a in its advance, retains the detent in displaced or ineffective position, until the carrying member is again cocked by the resetting member 613, to permit the spring-pressed detent to restore to effective position in front of the shoulder 610^p on its carrying member. The displacement of the detent may occur at any time during the retirement of the drive members, on the return stroke of the main drive shaft in direct carrying operations, and when this happens, the detent remains displaced until the carrying member is cocked at the end of the succeeding forward stroke, and even though, as in cross-carrying operations, a detent is not displaced until the end of the return stroke of the main drive shaft, or the beginning of the succeeding forward stroke, at which times the counters are engaged with their carrying members 610^a the detent remains displaced until its carrying member is cocked, immediately subsequent to the disengagement of the counters 490^x and the carrying members 610^a and their engagement with the drive members 410, at the end of the forward stroke of the main drive shaft.

Owing to the synchronism of operation of the parts, the discharged carrying members 610^a are cocked intermediate each engagement of the counters and drive members, so that in successive adding operations, there is no danger of lost carries through the passage of counters and their trip members 411 from the "9" to the "0" position while the carrying members 610 are discharged.

But it is frequently desired to take a total or clear the counters immediately after an operation during which one or more of the carrying members have been discharged.

Owing to the lost motion, however, slight, which is unavoidable in the manufacture and assembly of machines in bulk, considerable adjustment of the detents and their releasing and latching lugs has been required heretofore, to enable the releasing lugs to arrest the

trip members in a totaling or clearing operation, when the detents are displaced, and the contact between the trip members and release lugs is often so slight that wear taking place between the releasing lug and trip member 411 will permit the release lugs to clear the trip members when the counters 490^x are returning to zero, while in mesh with their drive members 410.

The disadvantages of such wear are not so serious where totaling and clearing operations are undertaken when the detents are all in their lower effective positions, and for this reason it has been customary in the past, to provide means to enforce an idle stroke of the main shaft 200 between the last accumulating operation and a totaling or clearing operation, to return the carrying members discharged during the last accumulating stroke, and thereby enable the displaced detents to return to their lower, effective positions, at which time, their release lugs 612^s lie nearer the trip members 411 when the latter and the counters are engaged with the drive members 410.

There are two objections to the idle stroke, one of which is that the paper is fed on such stroke, which leaves a blank space between the last amount accumulated, and the total. Prior to the use of designating signs, this blank space served in a measure to indicate that the following amount was a total, but with the advent of sign printing to designate totals, this dubious advantage became obsolete. The blank space, while negligible in itself, results, in the aggregate, in a considerable waste of paper, and by eliminating the necessity for such idle stroke, a saving of paper is effected.

Another objection is the loss of time caused by the necessity for taking this blank or idle stroke.

By the provision of the flexible detent, it will be obvious that as soon as the trip member 411, after tripping the detent, escapes past the release lug 612^s, the carrying member 610^a having partially advanced until arrested by the carrying-resetting bar 613, so that the latching lug 612^m rides on top of the shoulder, the spring 681 swings downwardly the trigger which carries the combined release lug and abutment 612^s until the upper end of the opening 612^r contacts the connecting pin 651. Such restoration of the release lug and abutment 612^s is only partial, or in other words, the lug does not restore to the same position which it occupied prior to the displacement of the detent, but it is sufficient to bring the release lug and abutment so far within the path of travel of the trip cam 411 as to provide a firm contact therefor and prevent it from slipping past, when totaling and clearing operations are undertaken while any of the carrying members 610^a are in discharged position.

It has been explained how the tripped carrying members 610^a advance at the end of an adding operation, and are not reset until the end of the succeeding forward stroke, 5 immediately after the disengagement of the counters 490^x from the carrying members. Also, that in totaling and clearing operations, the counters disengage from their carrying members at the beginning of the forward stroke. Assuming that one or more carrying members have been tripped on the preceding operation, and are holding the detents 612^s and triggers 612^e in their idle positions, the dropping of the counters 490^x and 15 their trip cams 411 into mesh with their drive members 410 in a totaling operation, for example, effects the greatest separation between the trip cams and the release lugs 612^s on the triggers 612^e. My flexible trigger 20 takes up a portion of this distance and thus permits a totaling and clearing operation immediately following an accumulating operation, and insures a firm contact between the trip cam 411 and the release lug 612^s. 25 By permitting such procedure, the necessity for an idle stroke is eliminated, and hence the feed of paper is avoided and time is saved.

The elimination of the necessity for taking an idle stroke is of particular value in the multiple counter machine disclosed in the Pentecost and Fisher application above-mentioned, equipped with a counter-selecting and a subtracting mechanism, as well 30 as totaling and clearing mechanisms, owing to the fact that the idle stroke-enforcing mechanism became effective in such former device, not only after any accumulating operation of the machine, to prevent totaling 35 and clearing operations immediately subsequent thereto, but also when the adjustment of the counter-selecting mechanism is changed, as well as when the subtracting mechanism is adjusted for operation. My 40 invention will permit the elimination of the idle stroke-enforcing mechanism from the multiple counter machine.

It has been stated that the counters engage their drive members under two different 50 conditions, namely, at the end of the forward stroke of the main drive shaft, in adding items, when the drive members have advanced until arrested by the key-set stops; and secondly, in totaling operations, on 55 which the counters engage their drive members at the beginning of the forward stroke, prior to the advance of the drive members.

In the Pentecost and Fisher machine, there is still another condition affecting the engagement of the counters and their drive members, which arises in subtracting operations.

Frequently, a subtracting operation immediately succeeds an adding operation in 65 which one or more carrying members have

been discharged. In such subtracting operation, the drive members advance on the forward stroke of the main drive shaft 200, until arrested by the feelers 413^s set in their paths, and the active set of counters drops 70 into mesh with the advanced drive members at the end of the forward stroke of the main drive shaft, as in the ordinary adding operation. It may happen that because of slight variations in manufacture, the workman, in adjusting the parts to obtain the proper mesh or engagement of the counter pinions 435 and drive members 410 in adding items and in totaling and clearing operations, has been forced to so arrange the 75 parts that the feelers will arrest the drive members in such positions relatively to the counter pinions 435, that when the latter drop into mesh with their drive members, the pinion teeth will strike against the front 80 slopes or faces of the teeth of the drive members 410, which, as the counter pinions 435 settle in place, will turn the active set of counters 490, 490^x anti-clockwise and press the trip members 411 of those counters which 85 register zeros, against the releasing lugs 612^s of the displaced detents.

In rapid operations, this sequence of events occurs almost instantaneously and will result in further displacing the detent 95 to permit the trip member to pass the releasing lug, (unless it has a firm and adequate contact therewith), and render the subtraction incorrect.

My invention is designed to prevent any 100 inaccuracies in subtracting operations due to this cause, because, by the use of the flexible detent construction, the releasing lug 612^s of the trigger 612^e, due to the play afforded by the enlarged opening 612^r relatively to the connecting pin 651^b, automatically adjusts itself into the path of the trip member 411 to arrest the latter, whether the detent is effective or ineffective.

Changes may be made in the form and arrangement of the several parts set forth without departing from the spirit and scope of the invention.

What I claim as new, is:—

1. In a calculating machine, the combination with a counter of lower denomination; a trip member carried thereby; a counter of next higher denomination; a carrying member therefor; means to drive the carrying member in one direction to turn the counter 115 of higher denomination; and means to restore the carrying member to normal position; the counters adapted to shift from and toward the carrying member; of a flexible detent adapted to lock the carrying member 120 in its restored position, and including a latch member journaled to swing into and out of the path of the carrying member, and a release lug flexibly connected with the latch 125 for relative movement and normally lying 130

in the path of the trip member of the counter of next lower denomination.

2. In a calculating machine, the combination with a series of carrying members; 5 means to drive the carrying members in one direction; means to restore the carrying members in the opposite direction, to cock the carrying members; a series of rotatable counters shiftable toward and from the 10 carrying members in a direction at an angle to the direction of travel of the carrying members; and trip members carried by the counters; of a series of inherently flexible detaining means adapted to lock the respective carrying members in cocked position, 15 and to automatically maintain effective relation with the trip members as the latter shift with the counters relatively to the carrying members.
- 20 3. In a calculating machine, the combination with a series of carrying members; means to drive the carrying members in one direction; means to restore the carrying members in the opposite direction, to cock 25 the carrying members; a series of rotatable counters shiftable toward and from the carrying members in a direction at an angle to the direction of travel of the carrying members; and trip members carried by the 30 counters; of a series of inherently flexible detaining means adapted to lock the respective carrying members in cocked position, and to automatically maintain effective relation with the trip members irrespective of 35 the positions of the trip members and detents relatively to each other.

4. In a calculating machine, the combination with a carrying member, means to drive the carrying member; means to restore the carrying member to cocked position; a counter of lower denomination; a trip member 40 mounted to travel therewith; and a counter of next higher denomination with which the carrying member coöperates, the counter 45 and trip member adapted for bodily movement toward and from the carrying member; of a flexible detent, including a latch to releasably engage the carrying member for the counter of higher denomination, to 50 maintain the latter in cocked position, and displaceable by the trip member; and a combined release and abutment lug shiftable relatively to the latch, to maintain effective 55 relation with the corresponding trip member irrespective of the position of the counter and trip member relatively to the carrying member.

5. In a calculating machine, the combination with a carrying member; means to drive 60 the carrying member; means to restore the carrying member to cocked position; a counter of lower denomination; a trip member mounted to travel therewith; and a counter of next higher denomination with which the carrying member coöperates, the counter and 65

trip member adapted for bodily movement toward and from the carrying member; of a latch to releasably engage the carrying member for the counter of higher denomination to maintain the latter in cocked position, and displaceable by the trip member; and a combined release and counter-arresting lug having a limited movement relatively to the latch to enter the path of the trip member irrespective of the positions of the trip member and latch relatively to each other.

6. In a calculating machine, the combination with a carrying member; means to drive the carrying member; means to restore the carrying member to cocked position; a counter of lower denomination; a trip member mounted to travel therewith; and a counter of next higher denomination with which the carrying member coöperates, the counter and trip member adapted for bodily movement toward and from the carrying member; of a suitably journaled latch to releasably engage the carrying member to maintain the latter in cocked position, and displaceable by the trip member; a suitably journaled release and counter-arresting lug connected to have a limited travel relatively to the latch, to maintain a position in the path of the trip member as the latter shifts 95 with its counter toward and from the carrying member; and a spring to enforce the relationship between the lug and the trip member.

7. In a calculating machine, the combination with a carrying member; means to drive the carrying member; means to restore the carrying member to cocked position; a counter of lower denomination; a trip member mounted to travel therewith; and a counter of next higher denomination with which the carrying member coöperates, the counter and trip member adapted for bodily movement toward and from the carrying member; of a latch to releasably engage the carrying member to maintain the latter in cocked position, and displaceable by the trip member; and a shiftable lug having a pin and slot connection with the latch and adapted to maintain effective relationship with the trip member irrespective of the position of the counter relatively to the latch.

8. In a calculating machine, the combination with a carrying member; means to drive the carrying member; means to restore the carrying member to cocked position; a counter of lower denomination; a trip member mounted to travel therewith; and a counter of next higher denomination with which the carrying member coöperates, the counter and trip member adapted for bodily movement toward and from the carrying member; of a latch to releasably engage the carrying member to maintain the 130

- latter in cocked position, and displaceable by the trip member; a shiftable lug having a pin and slot connection with the latch and adapted to maintain effective relationship with the trip member irrespective of the position of the counters relatively to the latch; and a spring connected to the lug to shift it toward one end of its limit of travel relatively to the latch to insure the relationship between the lug and the trip member. 5
9. In a calculating machine, the combination with a series of carrying members; means to drive the members in carrying operations; means to restore the carrying members to cocked position; a series of counters shiftable from and toward the carrying members; means to turn the counters in opposite directions; and trip members mounted to shift and turn with the counters; of latches to releasably maintain the respective carrying members in cocked position, and displaceable by the trip members; and combined latch release and counter-arresting members connected to 15 their respective latches to have a limited movement relatively thereto, the combined release and counter-arresting members adapted to maintain effective relationship with the trip members irrespective of the relative positions of the counters and latches. 20
10. In a calculating machine, the combination with a counter of lower denomination; a trip member controlled thereby; a counter of higher denomination; a carrying member therefor; and means to operate the carrying member; of a flexible detent adapted to lock the carrying member in one of its positions, and including a latch shiftable 25 into and out of effective position relatively to the carrying member, and a release lug connected with the latch for relative movement, and normally lying in the path of the trip member of the counter of lower denomination. 30
11. In a calculating machine, the combination with a series of counters; carrying members therefor, the counters shiftable toward and from the carrying members; means to drive the carrying members; means to retire the members to cocked position; means to turn the counters in one direction or the other; and trip members mounted to shift, and to turn coincidently with the 35 counters; of displaceable latches to releasably engage their respective carrying members to maintain them in cocked position, the latches adapted for movement toward and from the counters, and when displaced, adapted to ride on and be held displaced, by the carrying members; and combined release and counter-arresting members connected with their respective latches to have a limited movement relatively thereto, to 40 enable the combined release and counter-arresting members to lie in the paths of their corresponding trip members irrespective of the relative positions of the latches, the counters and the carrying members. 45
12. In a calculating machine, the combination with a series of drive members; a series of carrying members adapted for reciprocating movement; a series of rotatable counters shiftable in a direction at an angle to the direction of travel of the carrying members, to engage and disengage the carrying members and the counters alternately; and trip members shiftable and rotatable with the counters; of a series of sectional detents to lock the several carrying members at one end of their travel; means to connect the respective sections of the several detents, for relative movement, whereby to enable one of the sections of each detent to enter the path of its corresponding trip member irrespective of the positions of the trip members and detents relatively to each other. 50
13. In a calculating machine, the combination with a series of drive members; a series of movable carrying members spaced apart from the drive members; a series of counters interposed between the series of drive members and carrying members, and bodily shiftable in a direction at an angle to the direction of travel of the carrying members, to engage and disengage the latter, and the drive members; and trip members connected with the respective counters to turn and shift bodily therewith; of detents for the several carrying members, the detents each including a latching member to retain the corresponding carrying member in set position, a trigger carrying a release and counter-arresting lug, and a loose connection between the trigger and latch; a spring to yieldingly hold the latching member effective; and a spring to yieldingly hold the trigger at, and return it to, one limit of its movement relatively to the latching member, to maintain the release and counter-arresting lug in the path of the corresponding trip member. 55
14. In a calculating machine, the combination with a series of carrying members; a set of rotatable counters bodily shiftable into and out of engagement with the carrying members; a trip member associated with each counter to rotate and shift therewith; and means to drive the counters; of a detent for each carrying member to releasably retain it in set position, the detents each including a shiftable latch to restrain the carrying member; a trigger provided with a latch release and counter-arresting lug; and a connection between the trigger and latch to permit relative movement therebetween, whereby to enable the latch release and counter-arresting lug to lie in the path of its corresponding trip member irrespec- 60

tive of the relative positions of the trip member and latch.

15. In a calculating machine, the combination with a series of carrying members; 5 means to drive the carrying members in one direction; means to reset the carrying members to cocked position; a series of rotatable counters shiftable into and out of engagement with the carrying members; and 10 trip members traveling with the counters;

of a series of flexible detainers displaceable by the trip members, and normally effective to lock the respective carrying members in 15 cocked position; and to automatically maintain effective relationship with the trip members irrespective of the position of the latter relatively to the carrying members, and irrespective of the positions of the detainers relatively to the carrying members. 20

CHARLES BIRTH.
